GARMENT FINISHING DEVICE

Julian C. Shaw and Harry E. Blettner, Cincinnati, Ohio, assignors to The American Laundry Machinery Company, Cincinnati, Ohio, a corporation of Ohio

Application February 14, 1946, Serial No. 647,611

16 Claims. (Cl. 223—70)

1

This invention relates to garment finishing devices, and more particularly to that type of device in which the garment is supported upon or around a hollow fabric bag through which hot air or steam, or both, may be caused to flow to the garment for finishing it in a well-known manner.

One object of the present invention is to improve the bag or form upon or around which the garment is dressed, by reinforcing it so as to increase its life, and strengthen it against the strains and stresses resulting from the pressure of air and steam supplied to it.

Another object is to provide an improved bag or form of the character described, including means for controlling expansion of the bag by the fluid pressure within it.

Still another object is to provide an improved bag of the type described, including reinforcing members and operating means therefor so arranged as to control and limit bag inflation either automatically or under control of the operator, as will more fully appear.

Still another object of the invention is to provide an improved garment steaming bag of the kind described, including reinforcing ribs and operating means therefor which are so arranged as normally to bias the bag toward collapsed condition, but which are yieldable to permit the bag to expand under the influence of inflating pressure.

Still another object of the invention is to provide a garment steaming bag of the character described, provided with a series of circumferentially spaced longitudinally extending ribs which compel expansion of the bag to scalloped form, so that the bag contacts with the garment, if at all, only along spaced lines, instead of continuously.

Other objects of the invention are in part obvious and in part will appear more in detail hereinafter.

In the drawings,

Fig. 1 represents a side elevation of one embodiment of the invention, parts being broken out and in section to expose interior construction;

Fig. 2 is a front elevation of the upper portion of the device, similarly broken out;

Fig. 3 is an elevation of the upper portion of the device, corresponding to Fig. 1, and illustrating another arrangement;

Fig. 4 is a detail elevation, from the left in Fig. 1, and on a larger scale, and illustrating the manually operated device for controlling bag inflation;

2

Fig. 5 is a side elevation thereof, partly in section, on the line 5—5, Fig. 4;

Fig. 6 is a detail sectional plan view on the line 6—6, Fig. 2; and

Fig. 7 is a similar view on the line 7—7, Fig. 2.

The device shown in the drawings comprises a suitable base 10 adapted to rest upon the floor or other suitable support and upon which is mounted a hollow casing 11 enclosing a hot air chamber 12, a steam supply nozzle 13, a heating device of hollow pail form, marked generally 14, and which serves both to heat the air stream and to vaporize moisture and condensate and thus insure a dry steam supply, and a controlling valve device 15, operated by handle 16, for the air stream, which is produced by a fan or blower 17 operated by motor 18. 19 indicates a valve for controlling the flow of steam to nozzle 13, said valve being actuated by controlling pedal 20.

The parts so far described may be constructed and arranged in any suitable manner, such for example as described more in detail in a patent of George W. Johnson for Garment finishing apparatus, granted May 27, 1947, No. 2,421,203, to which reference may be had if desirable or necessary.

Mounted upon the upper end of the heating member 14 is an upright post 21 provided with supporting feet 22 anchored on member 14 and provided at its upper end with outwardly extending bars 23 which support the shoulder portions of a hollow bag 24. This bag is the one upon which the garment to be finished is dressed. It may be of any suitable shape, but usually is of the general shape of the particular garment. That shown is adapted particularly for finishing ladies' gowns or dresses, and comprises an upper waist portion 24' tapering downwardly to the belt line 25, as shown in Fig. 2, and having its wall flaring or enlarging downwardly below the belt line to provide the skirt portion 26 which, at its lower or hem end, has an expanded portion 27, including surplus material, the lower end of which is gathered in and secured, as by a clamping ring 28, to a sleeve or collar surrounding an opening at the top of the heating chamber 12 and forming a means of communication between said heating chamber and the space within the bag. The bag is usually made of canvas or other suitable porous flexible fabric.

Within the skirt portion of the bag we mount suitable means for reinforcing it and controlling its inflation. As illustrated the inner surface of the skirt portion of the bag, at intervals circumferentially thereof, is provided with a vertically extending reinforcing and stiffening rib, such as

a fairly strong wire or rod 29. Any number thereof may be used, the drawings showing eight. Each of these rods is enclosed in a long narrow envelope 30 formed by parallel rows of stitching attaching a strap to the body of the bag.

The several rods 29 at their upper ends are pivotally connected to arms 31 pivoted on a ring or sleeve 32 fixedly secured to the post 21, and at a lower point are provided with ears or lugs 33 pivotally connected to links 34 which, in turn, are pivoted to arms 35 on a sleeve 36 slidably mounted on the post 21. The arrangement is something like that of the ribs of an ordinary umbrella.

As described in the said Johnson application above referred to, a garment is finished in this apparatus by dressing or arranging it upon or around the bag while the latter is in collapsed position, as shown in Fig. 1. Then hot air, or steam, or both are introduced or supplied to the chamber within the bag to expand it and permit the flow of the hot air or steam, or both, through the fabric of the bag to and through the garment.

In the present arrangement the set of ribs 29, with the envelopes in which they are enclosed, and the operating devices connected to said ribs, are utilized not only to limit or control expansion or inflation of the bag, but also to assist in the distribution of air or steam to the garment.

When the bag is collapsed the sleeve 36 lies in its upper position, shown in Fig. 1. When fluid pressure enters the bag it expands or becomes inflated, and the sleeve 36 moves downwardly and links 34 assume more inclined positions as shown in Figs. 2 and 6, where the bag is fully inflated. Here the fabric of the bag expands outwardly into the form of a series of scallops or corrugations 40, Fig. 6, separated by the valleys in which the ribs and envelopes are located. Thus, the bag contacts the garment, if at all, in its skirt portion, only at the crests of the scallops or corrugations, permitting more thorough distribution of the hot air and steam to the entire area of the material of the garment.

Usually we provide the apparatus with biasing means yieldably opposing bag expansion and tending to collapse it, although this is not always essential. This means may be employed to physically contract the bag when the supplies of air and steam are turned off.

In Fig. 1 we connect the sleeve 36 to one end of a flexible band, such as a wire or cable 41, the upper end of which is fastened to and travels in the groove of a pulley 43 rotatably mounted on a shaft 44 and lying within a small casing 45 secured to the upper end of the post 21. Pulley 43 is secured to one end of a biasing spring 46, shown as a coil spring, the other end of which is secured to the casing, and said spring always tends to turn the pulley in a direction to wind up the cable, elevate sleeve 36 and thus collapse the bag. Pulley 43 is also connected to a sleeve 47 extending to the outside of the casing where it is provided with a handle 48 fastened with an arm 49 and a pin 50 adapted to enter any one of a series of holes 51 in a stationary plate 52. Shaft 44 at one end is threaded into a wall of the casing 45 and on its outer end supports a freely rotatable knob 53. It will also be understood that pulley 43, sleeve 47 and handle 48 as a unit, are both slidably and longitudinally movable on the shaft 44, and more specifically may be moved to the left on said shaft against the endwise pressure of spring 46 so as to disengage pin 50 from the holes 51.

Assuming the bag collapsed with the garment dressed upon it ready for finishing, it will be ob-

served that outward movement of the ribs 29, and bag expansion, are stopped or prevented by the interlocking of pin 50 in one of the stop holes 51. The operator turns on the air supply to inflate the bag. But this operation is performed with carefully controlled bag expansion. The bag is large or full enough to receive or accommodate the maximum size of garment to be finished. Thus, if it is permitted to expand freely, without restraint, within a small sized garment, the garment may become unduly stretched, wrinkled or otherwise distorted.

With the arrangement described when the supply of compressed air is turned on, the operator applies the palm of his hand to knob 53 and with his fingers pulls out handle 48. This releases the expansion restraining lock by withdrawing pin 50 from the hole 51 in which it lies. The air supplied under pressure immediately becomes effective to expand the bag and at the same time rotate pulley 43, sleeve 47 and handle 48 against the biasing effect of spring 46. To assist the operator in controlling or regulating bag expansion, the arm 49 is made to serve as a pointer traveling over a scale 54 indicating different positions or degrees of expansion. When the bag has expanded sufficiently in the opinion of the operator, either as indicated on the scale or as evidenced by the effect upon the garment itself, the operator releases handle 48 and permits the pin 50 to enter another of the stop holes 51 and thus prevent further bag expansion. Bag expansion usually is produced progressively, by a series of steps, performed in succession, each permitting the bag to expand a little more until it finally comfortably fills the garment without unduly stretching or distorting it. The expanded bag fills the garment, but contacts with its skirt portion, with light pressure, only along a series of lines at the crests of the scallops, between ribs, thus avoiding the production of circumferential or other wrinkles. Beyond this point it cannot go, even though the air or steam valve is opened wide enough to provide full supply. Consequently, when the operator has permitted controlled bag expansion to the right point, and has locked the expansion restraining means, no special attention is necessary during either steaming or drying.

When the finishing operation is concluded, the operator turns off the air and steam and again pulls out handle 48 to release the lock pin 50. The bag is then collapsed, either by the effort of the operator, or by permitting biasing spring 46 to move the ribs 29 inwardly, and the finished garment is removed from the form.

Fig. 3 shows a simpler arrangement in which the sleeve 36 is connected to one end of a tension spring 55, the other end of which is adjustably secured, as by screw 56, to a small bracket on the post 21. Here, the tension of the spring is adjusted so that it is sufficient to fully collapse the bag. When pressure is turned on, of air or steam, the bag expands immediately, the amount of expansion being limited by controlling or regulating the rate of air or steam supply and the consequent tension applied to the spring, as will be readily understood.

In both forms described, the bag is reinforced at intervals circumferentially, is caused to assume an scalloped form and its expansion or inflation is controlled in the manner described.

Other advantages of the invention will be apparent to those skilled in the art.

What we claim is:

1. A finishing device of the character described,

comprising a base having an open supporting ring, a bag having one end open and secured to said ring, means for causing the flow of a gas under pressure through said ring into the space within said bag, a series of ribs distributed at intervals around said bag and secured thereto, and yielding means connected to said ribs and opposing bag inflation.

2. A finishing device of the character described, comprising a base having an open supporting ring, a bag having one end open and secured to said ring, means for causing flow of a gas under pressure through said ring into the space within said bag, a series of ribs distributed at intervals around said bag and secured thereto, yielding means connected to said ribs and opposing bag inflation, said means including a post supporting the upper end of said bag, a member slideable on said post, and a series of arms, one for each rib, connecting said member and ribs, and a spring effective upon said member.

3. A finishing device of the character described, comprising a vertical post, a hollow bag having its upper end supported by said post and its lower end open, means for supplying a stream of gas under pressure to the open lower end of said bag, a ring slideable on said post and provided with a series of radial arms connected at intervals to said bag, and yielding means supporting said ring.

4. A finishing device of the character described, comprising a vertical post, a hollow bag having its upper end supported by said post and its lower end open, means for supplying a stream of gas under pressure to the open lower end of said bag, a ring slideable on said post and provided with a series of radial arms connected at intervals to said bag, yielding means supporting said ring, and adjustable stop means limiting bag inflation.

5. A finishing device of the character described, comprising a support provided with a base having an open supporting ring, an elongated bag having one end open and secured to said ring, means for causing the flow of a gas under pressure through said ring into the space within said bag, and a series of ribs distributed at intervals around said bag, each thereof extending longitudinally of the bag and being attached at several points along its length to the bag and loosely connected at one end to the support, said ribs preventing outward movement of the bag material where they are attached to it and being adjustable inwardly and outwardly to various positions to vary the bag size when inflated.

6. A finishing device of the character described, comprising a base having an open supporting ring, a bag having one end open and secured to said ring, means for causing the flow of a gas under pressure through said ring into a space within said bag, a series of ribs distributed at intervals around said bag and attached thereto, and adjustable stop means connected to said ribs and limiting bag inflation.

7. Garment finishing apparatus, comprising a flexible porous bag upon which garments of various sizes may be dressed, means for causing the flow of a treating gas to the space within said bag in quantity sufficient to fully expand the same and also supply excess gas for distribution to and flow through the bag and garment for treating purposes, and means operatively associated with the bag and effective upon it at a plurality of points distributed both circumferentially and longitudinally over its entire garment supporting area for limiting bag expansion at such points to a degree short of full bag ex-

pansion predetermined by the operator but permitting limited ballooning effect upon the bag between such points, whereby bag expansion may be controlled and adapted to any of various sizes of garments without stretching or distorting the same.

8. Garment finishing apparatus of the character described, comprising a base provided with an open supporting ring, an elongated flexible porous garment supporting bag having a skirt portion open at its lower end and secured to said ring, means for causing the flow of gas under pressure through said ring and bag opening into the space within said bag, and restraining means supported upon the base for movement outwardly from and inwardly toward the bag center and having portions which simultaneously engage the bag at various points distributed both circumferentially and longitudinally of the entire area of its skirt portion and which thus are movable with the bag material but also are effective to oppose bag inflation caused by the pressure of the gas supplied to it.

9. Garment finishing apparatus of the character described, comprising a base provided with an open supporting ring, an elongated flexible porous garment supporting bag having a skirt portion open at its lower end and secured to said ring, means for causing the flow of gas under pressure through said ring and bag opening into the space within said bag, and restraining means mounted upon the base and having portions which simultaneously engage the bag at various points distributed both circumferentially and longitudinally of the entire area of its skirt portion and which thus are movable with the bag material but also are effective to oppose bag inflation caused by the pressure of the gas supplied to it, and adjustable stop means operatively connected to said restraining means for positively limiting both outward movement thereof and accompanying bag inflation to any degree predetermined by the operator.

10. Garment finishing apparatus, comprising a flexible porous bag having a skirt portion upon which garments of various sizes may be dressed, means for causing the flow of a treating gas to the space within said bag, and a series of supporting elements engaging the bag at points distributed circumferentially and longitudinally of its skirt portion and limiting outward bag movement at such points but permitting it between them, whereby the expanded bag presents to the garment a series of rounded bulges contacting it at separated intervals.

11. Garment finishing apparatus, comprising a base, a flexible, expandible and collapsible porous bag having an open bottom and secured to the base, means for supporting the bag in upright position upon the base, means for supplying garment treating fluid under pressure through the open bottom of the bag to the space within it for both expanding the bag by the ballooning effect and causing the flow of fluid to and through the garment through the material of the bag, control means therefor, yieldable bag collapsing means operatively associated with the bag and tending to bias it toward collapsed position, stop means effective upon the bag for limiting bag expansion in any of the various positions to which it may be expanded, and operator operated means for releasing said stop means, whereby selectively the bag either may be controllably expanded to any degree predetermined by the operator or

may be permitted to collapse upon release of the fluid pressure.

12. Garment finishing apparatus, comprising a bag made of flexible porous material and provided with means for supplying a treating gas to the space within it and upon which bag a garment may be dressed, and reinforcing and stiffening means for said bag, comprising a series of elongated rib members distributed at intervals upon the bag and attached to it at a series of points spaced both longitudinally and circumferentially over the garment supporting area of the bag.

13. Garment finishing apparatus, comprising an elongated bag made of porous flexible material and provided with means for supplying a treating gas to the space within it, said bag being provided with a series of longitudinally extending elongated pockets distributed at intervals upon it, and an elongated stiffening rib in each of said pockets.

14. Garment finishing apparatus, comprising an elongated bag made of porous flexible material and provided with means for supplying a treating gas to the space within it, said bag being provided with a series of longitudinally extending elongated pockets distributed at intervals upon it, an elongated stiffening rib in each of said pockets, a post extending longitudinally through said bag for supporting it, and a ring mounted on said post to which all of said ribs are secured.

15. Garment finishing apparatus, comprising an elongated bag made of porous flexible material and provided with means for supplying a treating gas to the space within it, said bag being provided with a series of longitudinally extending elongated pockets distributed at intervals upon it and each extending longitudinally of the bag, an elongated stiffening rib in each of said pockets, a post extending longitudinally

5

through said bag for supporting it, and two rings mounted upon said post, one fixed thereto and the other movable thereon, said ribs being each secured at one end to the fixed ring and at another point to the movable ring.

16. Garment finishing apparatus, comprising a downwardly-flaring generally skirt-form bag made of porous flexible material and provided with means for causing the flow of a treating gas to the space within it, a series of ribs distributed at intervals around the bag and attached thereto, each rib extending vertically between the waist and hem of the bag, an operating member movable back and forth to which said ribs are connected for causing simultaneous inward or outward movement of all ribs according as said member moves in one direction or another, and operator operated stop means effective upon said movable member, said stop means being operable to control bag expansion by limiting outward rib movement to any desired position predetermined by the operator, thereby enabling him to accommodate the bag to any size or shape of garment being finished and to prevent undesired stretching or distortion thereof.
